UNITED STATES PATENT OFFICE.

WILLIAM COPELAND CROZIER, OF KNOXVILLE, TENNESSEE.

DISTRIBUTING-CASE.

SPECIFICATION forming part of Letters Patent No. 375,735, dated January 3, 1883.

Application filed June 10, 1887. Serial No. 240,942. (No model.)

To all whom it may concern:

Be it known that I, WILLIAM COPELAND CROZIER, a citizen of the United States, residing at Knoxville, in the county of Knox and 5 State of Tennessee, have invented new and useful Improvements in Distributing-Cases, of which the following is a specification.

My invention relates to a distributing case for letters for use in post-offices; and it consists in the construction and arrangement of the parts of the same, which will be more fully hereinafter described, and pointed out in the claims.

The object of my invention is to provide 15 ready means whereby letters may be distributed for delivery by carriers or for sectional delivery, whereby the distributers to boxes may obtain their mail apportioned to them without disturbing the distributer, and to economize space in front of the said distributer. I attain this object by the construction illustrated in the accompanying drawings, wherein like letters of reference indicate similar parts in the several views, and in which—

25 Figure 1 is a front view of my improved distributing-case. Fig. 2 is a rear elevation of the same. Fig. 3 is a transverse vertical section thereof. Fig. 4 is a horizontal section on the line $x x$ of Fig. 3.

30 The distributing-case is constructed with a suitable frame mounted upon suitable supports, as shown in the drawings. Upon the upper part of the frame A, and in convenient proximity to the depressed distributing-table A', a series of openings are formed, which register with a series of chutes, C C, which in turn engage with drawers a a , situated in the front part of the case, as shown in Fig. 1. Any number of these drawers a can be constructed as 35 may be desired, being arranged separate and apart from each other, and each having an independent chute, a' . These drawers a are for the reception of the section mail, and are situated on the same side of the cabinet or case 40 upon which the distributer stands, being fed through the openings a^2 . Above the openings a^2 a series of openings, a^3 a^4 , are arranged, which form the mouths of the chutes C, running to the boxes or drawers B, in which the carrier's 45 mail is deposited. These drawers B are in

like manner individually arranged, each having its chute separate and apart from the other, and as many thereof may be arranged in connection with each cabinet or case as may be desired. The divisional partitions are hinged 55 at the point F, so that they may be adjusted to increase the size of their throats, and are held in position by suitable latches, E. Above the openings a^3 and a^4 a series of pigeon-holes, a^5 , are arranged on each side of the case for 60 any purpose which may be desired in the distribution of the mail, and on the opposite side of the case a like series of pigeon holes a^6 are formed.

By the use of my improved device mail matter may be rapidly distributed into the several carriers' boxes, and obtained by the carriers therefrom without disturbing the distributer. By the construction of the plates the section mail can be separated and distributed 65 at the same time that the carriers' mail is being distributed, with a saving in time and labor.

By the use of my improved device mails are advantageously handled and distributed, time 70 and labor saved, and the device being simple in its construction and cheaply manufactured is rendered useful in connection with both small and large post-office deliveries.

The advantage in the use of my improvement is the economy in space and necessarily the economy in labor, for the reason that it enables the distributer to distribute to the same number of carriers and sections without moving so often or raising his eyes from the letters being distributed. By this means a distribution can be made to about three times as many carriers and sections in a given time as has heretofore been accomplished.

The novelty and utility of my improved device being obviously apparent, it is unnecessary to further enlarge upon the same herein.

Having thus described my invention, I claim—

1. A distributing-case consisting of the drawers a , independently arranged, and having individual chutes with openings a^2 , and the drawers B, similarly arranged, but opposite to the drawers a , substantially as described.

2. A distributing-case consisting of the draw- 100

ers a , having the chutes C , the partitions of which are adapted to be adjusted and increase the size of the said chute, the drawers B , and the pigeon-holes arranged in the upper part 5 of the case, substantially as described.

3. A distributing-case consisting of the series of drawers a , having the chutes C hinged at the points F , and the latches E , substantially as described.

4. A distributing-case consisting of the drawers a , having the individual adjustable chutes C , the drawers B , having the chutes of similar construction to the chutes C , the depressed table A , the pigeon-holes a^5 , and the pigeon-holes a^6 , arranged on the reverse side of the case to the pigeon-holes a^5 , substantially as described.

5. A distributing-case having a series of drawers and a series of independently-arranged individual chutes for said drawers, as set forth.

6. A distributing-case having a series of drawers and a series of independently-arranged individual chutes, the partitions of which are adjustable for the purpose of increasing the size of said chutes, as set forth.

7. A distributing-case consisting of the table A , the separate series of drawers a B , arranged on opposite sides, the independently-arranged and individual chutes C , for the drawers a B , which chutes open on opposite sides of the case, and the pigeon-holes a^5 a^6 in the upper part of the case above the table A , as set forth.

In testimony that I claim the foregoing as my own I have hereto affixed my signature in presence of two witnesses.

WILLIAM COPELAND CROZIER.
